PYROTECHNIC DISPLAY

Ray C. Hitt, Seattle, Wash.

Application October 13, 1931, Serial No. 568,595

2 Claims. (Cl. 102—20)

This invention relates to pyrotechnic displays; and more particularly, to what is commonly known as "Sparklers".

The principal object of this invention is to provide a casing in the form of a tube of combustible material filled with fireworks composition, and sealed at both ends. The outer casing is of slower burning texture than the fireworks composition so that although the outer casing is consumed during the burning operation, there is always a slight shell extending above the burning composition so as to form a chamber in which gases will form. This results in the flame being forced out in the form of a spray as contrasted with the illumination produced by what are commonly known as "Lights".

Heretofore "Sparklers" have been formed by placing the fireworks material on a wire. This is highly objectionable in that even though the sparks coming from the "Sparkler" are harmless, the residue left on the wire is very hot and often results in serious burns. This is also true of the wire itself.

"Lights" of the fusee type contain an outer casing and are filled with a fireworks composition, but instead of obtaining the "chimneying" effect as produced in my invention, only a soft light results. This is primarily due, I believe, to the fact that the outer casing burns at the same rate as the fireworks composition.

Another object is to provide a display that is safe to handle and that is devoid of the objectionable features now found in such devices.

Other objects will be disclosed in the specification and claims forming a part of this application.

In the drawing:

Figure 1 is a side elevation of the display;

Figure 2 is a side elevation with parts broken away;

Figure 3 is a vertical fragmentary section showing the display ignited and the action of the fireworks composition;

Figure 4 is a top plan of the display; and

Figure 5 is a horizontal section taken on the line 5—5 of Figure 3.

Referring to the drawing, in which similar parts are designated with like numerals:

Numeral 6 designates a display of the "Sparkler" type having a casing 7 formed of thin paper in the form of a spiral. It is to be understood that this casing is formed in this way merely for convenience, and my invention is in no way limited to this construction.

In order to retard the free burning of the

casing 7, I coat the same with paraffin 8, which coating may be any other substance of similar characteristics.

It has been found that the amount of paraffin used enters into the successful manufacture and functioning of the device. In a display having a wall 1/64th of an inch in diameter with an interior diameter of composition of 9/64th of an inch, there should be sufficient paraffin so that when the same is melted by the burning of the composition it will penetrate the composition to the depth of about $\frac{1}{16}$ of an inch before the fire reaches the same. Ordinary "Sparkler" or "Light" composition 9, such as barium nitrate, 16 parts, chlorate of potash, 14 parts, red gum, 15 4 parts, aluminum, 8 parts is used which will give a green display; and a red display may be obtained by using the following ingredients—strontium nitrate, 16 parts, chlorate of potash, 10 parts, red gum, 5 parts, and aluminum, 7 parts. 20 This composition is used in the casing 7, and both ends 10 and 11 of the casing are sealed with the retarding medium paraffin so as to prevent the escape of the fireworks composition and also to protect the same from moisture.

As actually used, either end of the display 6 may be ignited, the paraffin melting until the fireworks composition 9 is exposed so that in conjunction with the inflammable casing 7, the display starts functioning.

As shown in Figure 4, the fireworks material burns slightly faster than the outside casing, which results in gases set up by the burning fireworks composition being compressed and in turn forcing the flames out of the end of the 35 casing in the form of a fountain of spray. The paraffin will melt flowing into the fireworks composition and giving added effects.

By the use of thin paper and coating the same with paraffin, the same effect is obtained as if a thicker, slower burning casing were used, with the added advantage that the same is air and moisture proof. On the other hand, a thicker casing without the retarding material would still come within the scope of my invention.

I do not limit my invention to displays of the "Sparkler" type, as it is obvious that the same principle may be utilized in connection with other pyrotechnic devices. For instance, a wire may be furnished with my displays which may serve either as a handle by inserting the same in the unlighted end of the display, or may be inserted in the middle of the display, both ends of the display being ignited and the whole whirled to give a pin wheel effect.

What I claim as my invention is:

1. A pyrotechnic display comprising a thin casing treated with a slow burning material, a fireworks composition containing spark producing metallic particles in said casing, said casing and fireworks composition adapted to be ignited at one end of said casing, the casing being of slower burning material than said composition, a chimney formed by said slow burning casing, said chimney confining for a short duration gases formed from the burning composition, said gases forcing the flames from the burning composition out of said casing to give a sparkler effect.

15 2. A pyrotechnic display comprising a thin

combustible casing treated with a slow burning material, a fireworks composition containing spark producing metallic particles in said casing, said casing and fireworks composition adapted to be ignited at one end of said casing, the casing being of slower burning material than said composition, a chimney formed by said slow-burning casing, said chimney confining for a short duration gases formed from the burning composition, said casing being completely consumed and leaving no scoria, said gases forcing the flames from the burning composition out of said casing to give a sparkler effect.
